UNITED STATES PATENT OFFICE.

EDGAR WILLIAM BRANDT, OF PARIS, FRANCE.

PROJECTILE FOR SMOOTH-BORE GUNS.

Application filed February 19, 1925, Serial No. 10,413, and in France January 12, 1925.

The present invention relates to projectiles which are chiefly adapted for use with smooth-bore guns or mortars which are loaded at the breech or the muzzle and wherein the charge is fired by means of a fixed or movable striker acting upon a cartridge which is mounted in the projectile itself.

The invention relates to various improvements in projectiles of this class whereby their stability and range will be augmented as compared with the known types, said improvements relating:

(a) To the shapes and the relative dimensions of the several parts of projectiles which have a tapered form and may be made of cast iron, steel-pig, or steel;

(b) To the arrangement of a set of grooves at the largest part of the projectile which does not fit exactly into the bore of the gun, said grooves providing a pneumatic joint between the projectile and the caisson when the shot is fired;

(c) To the disposition of the propulsive cartridge, in the tail part of the projectile with the addition of strengthening sleeves;

(d) To the construction of the fin device whereof the fins are longitudinally flanged at the outer edges in order to increase their total surface without augmenting their general size, and also to provide for the holding of additional propulsive charges employed in long-range firing.

The following description sets forth the various features of the invention, with reference to the appended drawings which are given by way of example and in which:

Fig. 1 is an elevational view of a projectile according to the said invention.

Fig. 2 is a longitudinal section of the same.

Fig. 3 shows the profile of the main body of the projectile together with a modified form of the band, and

Fig. 4 is a modification of the same.

Fig. 5 shows various shapes which may be employed for the grooves provided in the band.

Figs. 6, 7, 8 and 8^a are partial longitudinal sections showing various methods of attaching the tail piece to the main body of the projectile.

Fig. 9 is a cross section of the tail piece and of the fin device on the line 9-9 of Fig. 1.

Figs. 10, 11 and 12 show various forms of the cases containing the additional charges.

My said projectile essentially comprises a main body of cast iron, steel-pig or steel into whose front end is screwed a fuse of the percussion, time, or combination type, and to whose rear end is secured a tail piece provided with a suitable fin device. The said main body comprises three parts; at the front, a part 1 having an ogival profile and to which is secured the fuse 2, an intermediate part or band 3 whose largest diameter serves to determine the calibre of the projectile which is very slightly below the diameter of the gun bore, and a tapered part 4 which is conical or substantially conical and preferably convex, it being joined to the band portion 3.

The total length of the projectile with its fuse is comprised between three or four calibres for initial velocities of 50-200 meters per second and between four and seven calibres for initial velocities above 200 meters per second.

For initial velocities below 200 metres per second, the total length of the projectile is subdivided as follows: (1) the distance between the front end of the fuse, measured upon the centre line, and the middle plane M-N of the band, and which is taken as a unit or one part; (2) the height of the tail fin device and which is also equal to said unit; (3) the height of the rear portion of the body between the said middle plane of the band and the top of the tail is comprised between 1½ and 2 parts (1=3 to 4 calibres or 3,5 to 4 parts).

For initial velocities above 200 meters per second, the height of the fin portion is comprised between ½ part and 1 part. The other proportions will remain substantially as above indicated, for projectiles which are constructed for small initial velocities (L=4 to 7 calibres or 3 to 4 parts).

In the device shown in Figs. 1 and 2, the band of the projectile consists of a cylindrical portion extending outwardly of the front ogival portion 1 and of the rear portion 4, peripheral or circular grooves 5 being formed in the said cylindrical portion, the said grooves having herein a square cross-section.

In Fig. 3, the front part of the said band is directly joined to the front ogival portion, and due to the absence of all ribs extending

from the ogival portion, an increased aerodynamic efficiency over what is afforded by the device shown in Figs. 1 and 2 will be obtained, at the same time facilitating the 5 penetration into the layers of air as well as the flow of the air along the projectile without friction or eddies.

For the manufacture of cast iron projectiles, the trimming will be facilitated if 10 the said belt extends somewhat outwardly of the ogival part, as shown in Fig. 4. The grooves shown in this figure are analogous to the grooves indicated in Fig. 3, but differ from what is shown in Figs. 1 and 2; Fig. 15 5 represents other shapes and dispositions of the said grooves.

In all cases, since the external diameter of the band—or the calibre of the projectile—is somewhat smaller than the diameter 20 of the bore of the gun, the said grooves comprise a flat portion at the front, the letter *a* indicating this portion upon the various figures of the drawings. The large base of the conical part forming the rear of the 25 main body of the projectile has a diameter which is somewhat smaller than the diameter of the trimmed band, so as to form a shoulder *b* between these two parts.

The gas which tends to escape between the 30 projectile and the gun tube when the shot is fired will meet with the shoulder *b* which will thus form a first obstacle. The gas will however pass between the tube and the first rib of the band and will thus attain the first 35 groove; this latter constitutes a region of larger cross section in which the gas expands and loses its velocity; by its impact against the annular surface *a* of the groove, the gas is driven back, at least partially, and 40 the first eddy is thus produced. Similar eddies are produced in the same manner in the successive grooves, so that the discharge of the gas is checked in an energetic manner.

45 Due to the pneumatic joint which is thus formed by the grooved band, the loss of gas escaping between the projectile and the gun tube will be reduced and the range will be thereby augmented; at the same time, the 50 propulsive action of the charge is made regular in virtue of the diminution in the variations of this action between the successive shots, which are due to losses of gas, and a greater accuracy in firing will be thus 55 obtained.

The approved action of the said pneumatic joint is due to the proper determination of the height of the said band and of the size 60 and number of the grooves formed therein; said action augments with the pressure of the gases produced by the combustion of the propulsive charge.

65 The known artillery projectiles have a general cylindrical shape with an ogival front part; at the rear, the base is termi-

nated by a plane transverse section, so that there will be formed in the rear of the projectile when in flight a considerable vacuum which has a marked retarding action.

In my projectile, the rear part 4 of the 70 body which has the tapered form will reduce the amount of the retarding action upon the projectile by obviating, or at least greatly reducing, the eddies at the rear; the streams of air, which are abruptly impelled and 75 pushed laterally by the front ogival part 1 and the band 3, will slide along the part 4 which moves forward in the region of the vacuum produced at the rear of the band. Due to the fact that the streams of air are 80 thus guided and brought to the rear part of the projectile without the formation of eddies, the projectile will offer a less resistance to forward motion than the known 85 artillery projectiles and will therefore possess a higher aerodynamic efficiency than the latter.

By reason of the tapered shape of the part 4, the weight of this portion will be much 90 reduced as compared with the weight of a projectile of like calibre having the cylindro-ogival profile. For this reason the 95 centre of gravity of the spindle-shaped body of the projectile according to the invention will be brought much in front of the middle point on the main centre line, whereby the aerodynamic stability of the projectile will be augmented.

At the rear of the said tapered portion 4, 100 more or less convex, is mounted a tail piece 6 having a tubular form and made of semi-hard steel or like material of great strength; the diameter of the said piece is considerably less than the diameter of the projectile, and its lateral walls are apertured as shown at 105 7. The said piece may be simply screwed to the rear of the main body, either internally, Fig. 2, or externally, Fig. 8^a. Figs. 6, 7 and 8 show by way of example various other 110 methods of securing the same, respectively by riveting, seating or soldering (or welding) i. e. by autogenous welding, electric welding, brazing and the like. In the case of riveting, Fig. 6, the fluidtight fit between the body of the projectile and the tail piece may be augmented by interposing a metallic or other packing member 8 covering the whole or a part of the contact surface of the two parts.

The tail piece 6 is open at the rear end for the insertion of a cartridge 9 containing the propulsive charge. In the said tail piece is formed, preferably near the outer end, a groove 10 (or a plurality of grooves), so that by the combustion of the propulsive charge the cartridge case will be pressed laterally into the said groove or grooves, and the cartridge will be drawn forward with the projectile, when leaving the gun, in a reliable manner and irrespectively of the

nature of the said cartridge case and the amount of the propulsive charge.

Within the cartridge case 9 is disposed a sleeve 11 of cardboard or analogous material which increases the strength as well as the fluidtightness of the said cartridge case. Due to the addition of the said reinforcing sleeve (or sleeves) the said cartridge case will possess a suppleness and an elasticity, 10 as regards punching effects, which it would not have were it simply made with thicker walls. With this arrangement, I am further enabled to provide a waterproof coating between the cartridge case and the 15 sleeve.

By the use of the said sleeve 11, I am enabled to accurately adjust the space provided for the powder constituting the propulsive charge, and this facilitates the manufacture of the cartridges and also provides for the folding down of the end of the same 20 in uniform conditions. Since the finished cartridges have a uniform length, the capacity of the expansion chamber at the rear 25 part of the tail piece 7 will be the same for all the projectiles. By the said arrangements, I obtain the uniform combustion of the propulsive charge and a uniform expansion of gases, whereby the firing is rendered more accurate. It should be noted 30 that the said important advantages can be had by the use of one or more sleeves disposed at the exterior of the cartridges inserted within the said tail piece.

Upon firing the shot, when the charge is set off by means of the fixed or movable striker of the gun, the cartridge case and its strengthening sleeve or sleeves will be punched in coincidence with the holes 7 in 40 the lateral wall of the tail piece, and the gas will escape laterally through the said holes.

The tail piece of the projectile serves as the support for a fin device which obviates 45 the use of a tail piece of great length which would be much affected by the wind, and it thereby affords an approved longitudinal and transverse stability and hence a great accuracy as to range and direction, as well 50 as a most reliable functioning of the percussion fuses. The fins are disposed at the extreme rear of the projectile whereby they are enabled to travel in air which has resumed the normal state or at least in which 55 the streams are parallel forwardly of the vacuum region formed in the rear of the said band. The several fins will thus act in conditions of maximum efficiency. The length of the fins is either greater than, 60 equal to, or less than that the length of the tail piece 6, and is determined by experiment in view of obtaining the most approved stabilizing conditions.

The fins 12 are attached to the said tail 65 piece 6 by riveting, soldering or welding,

or by like means, and have a relatively short length; the use of multiple fins compensates for their short length whereby a sufficient total surface will be provided while obviating the use of a limited number of fins 70 of considerable length for the obtainment of an equivalent surface. According to the invention, the number of fins employed is always greater than four.

Fig. 9 shows a form of construction in 75 which two adjacent fins are formed by a common sheet metal member which is secured to the said tail piece. The middle part of the said member has a sufficient width and has formed therein suitable holes 80 13 which register with the holes 7 in the lateral surface of the tail piece. In this form of construction, the fins necessarily have an even number; but if they are cast integral with the tail piece, an odd number 85 of fins may be provided, for instance 5, 7, 9, 11, 13 or 15 fins.

In order to obviate unequal reactions upon the said fins when the gases under pressure which, after punching the cartridge case 90 and the reinforcing sleeve or sleeves of the cartridge, proceed through the holes 7—13 and expand between the projectile and the tube of the said tail piece, the flow sections provided for the gases are substantially proportional to the volumes of the spaces comprised between the adjacent fins. 95

If, as shown in Fig. 9, all the holes are of equal size and if there are two holes at A and three holes at B, the fins will be so disposed that the volumes at A' and at B' will have substantially the ratio 2:3. 100

The fins 12 are flanged at 14 upon the whole or a part of their edge. The parts which are not thus flanged are rounded in 105 such manner as to facilitate the handling of the projectile. The flanged parts 14 serve to increase the rigidity of the said fins and will thus enable the same to hold their shape during transportation and handling. The 110 flanged parts serve chiefly to increase the total guiding surface of the projectile when in flight, and the additional surfaces are advantageously situated at the periphery of the projectile, i. e. in the region in which 115 the air has become perfectly calm by reason of the general shape of the projectile.

The flanged parts 14 also serve for the attaching of the cases containing the additional charges which are employed for long-range firing, said cases being held in an elastic manner between the said fins and in front of the holes 7—13 from which the jets of ignited gas are to be discharged. 120

The said cases are made in two parts and are constructed in various forms as shown by way of example in Figs. 10 to 12, and they are manufactured by casting or stamping of a plastic substance which is not subject to ignition in the open air such as a 125 130

material comprising a combination of cellulose compound and plastic substances; the said material is not hydroscopic nor subject, like celluloid, to spontaneous combustion at a relatively low temperature, and the walls of the said cases, even when thin, are enabled to withstand all handling, moisture, dust and dirt, thereby protecting the powder in an approved manner. After receiving the charge, the two parts of the case are cemented together by means of a suitable solution or solvent such as acetone optionally containing an amyl acetate varnish, for example.

When the shot is fired, the flames of the ignited gases will issue from the holes in the tail piece of the projectile, perforating the cases containing the additional charges, which are held by the flanges of the said fins. Due to the high temperature of the gases, the combustion of the said additional charges as well as their containing cases will be ensured, thus leaving no unconsumed residue.

Obviously, the said invention is not limited to the constructional forms hereinbefore described with reference to the appended drawings; the said forms are given solely by way of example and are susceptible of various modifications without departing from the spirit of the invention. In particular, it is evident that while the various improvements in projectiles above mentioned will contribute in a general manner to the increase in the aerodynamic efficiency of the projectiles, to their stability in flight, to the accuracy of the firing in range and direction, to the maximum range, and the like, the said improvements need not be employed simultaneously, and a given projectile, provided it comprises one or more of the said improvements, may be considered as being within the scope of the invention.

Having now described my invention, what I claim as new and desire to secure by Letters Patent is:

1. A projectile for smooth-bore guns comprising a body having an ogival front part and a truncated conical rear part connected at their bases, a fuse secured to said front part and a fin carrying tail part, the total length of said projectile being comprised between 3.8 and 4 calibres the length of the rear part of the body being comprised between 1.8 and 2 calibres and the length of the said tail part being less than 1 calibre.
2. A projectile for smooth-bore guns comprising a body having an ogival front part and a truncated conical rear part connected at their bases, a fuse secured to said front part and a fin carrying tail part, the total length of said projectile being comprised between 3.8 and 4 calibres, the length of the rear part of the body being comprised between 1.8 and 2 calibres and the length of the rear part of the body being comprised between 1.8 and 2 calibres and the length of

the said tail part being less than 1 calibre, the fins being secured on the tail in a region longitudinally separated from the rear part of the body of the projectile.

3. A projectile for smooth-bore guns comprising a body having an ogival front part and a truncated conical rear part connected at their bases, a fuse secured to said front part and a fin carrying tail part, the total length of said projectile being comprised between 3.8 and 4 calibres, the length of the rear part of the body being comprised between 1.8 and 2 calibres and the length of the said tail part being less than 1 calibre, the diameter of said fin arrangement being substantially equal to one calibre whereby a reliable guiding effect is obtained.

4. A projectile for smooth-bore guns an ogival front and a truncated conical rear part connected at their bases, a fuse secured to said front part and a short fin carrying tail part, a substantially cylindrical middle portion the diameter of which is equal to the calibre of the projectile and connecting said front and rear parts with one another and circular grooves provided on the periphery of said middle portion in planes at right angles to the axis of the projectile and adapted to create eddy currents of the propelling gases flowing around said middle portion each groove having an annular front wall perpendicular to the axis of the projectile, the lateral side of each groove tapering towards the rear end thereof.

5. In a projectile for smooth-bore guns, a body comprising an ogival front part and a tapered rear part, a tubular perforated tail part secured to said rear part, fins provided on the outer periphery of said tail part, a cartridge within said tail part and one or more reinforcing sleeves concentric with said cartridge.

6. In a projectile for smooth-bore guns, a body comprising an ogival front part and a tapered rear part, a tubular perforated tail part secured to said rear part, fins provided on the outer periphery of said tail part, a cartridge within said tail part and one or more reinforcing cardboard sleeves concentric with said cartridge.

7. In a projectile for smooth-bore guns, a body comprising an ogival front part and a tapered rear part, a tubular perforated tail part secured to said rear part, fins provided on the outer periphery of said tail part, a cartridge within said tail part, one or more reinforcing sleeves concentric with said cartridge and a fluidtight coating between said cartridge and said sleeves.

8. In a projectile for smooth-bore guns a body comprising an ogival front part and a tapered rear part, a tubular perforated tail part secured to said rear part, a cartridge within said tail part and a number of pairs of fins, greater than two, secured to the outer

periphery of said tail part, the two fins of each pair being cut in one metal sheet and the outer edges of said fins being flanged longitudinally over one part of or all their 5 length.

9. In a projectile for smooth-bore guns a body comprising an ogival front part and a tapered rear part, a tubular perforated tail part secured to said rear part, a cartridge 10 within said tail part and a number of fins, greater than four, provided on the outer periphery of said tail part, the outer edges of said fins being flanged longitudinally over one part of or all their length, and cases 15 containing additional charges carried by said tail part in front of the perforations therein, said cases being made of a material adapted to burn under the action of the combustion of said cartridge.
- 20 10. In a projectile for smooth-bore guns a body comprising an ogival front part and a tapered rear part, a tubular perforated tail part secured to said rear part, a cartridge within said tail part and a number of 25 fins, greater than four, provided on the outer

periphery of said tail part, the outer edges of said fins being flanged longitudinally over one part of or all their length and cases containing additional charges yieldingly clamped between adjacent fins, said cases being made of a material adapted to burn under the action of the combustion of said cartridge. 30

11. In a projectile for smooth-bore guns a body comprising an ogival front part and a tapered rear part, a tubular perforated tail part secured to said rear part, a cartridge within said tail part and a number of fins, greater than four, provided on the outer periphery of said tail part, the outer edges of said fins being flanged longitudinally over one part of or all their length and cases of a plastic cellulose compound 35 containing additional charges carried by said tail part in front of the perforations 40 therein.

In testimony whereof I have signed my name to this specification.

EDGAR WILLIAM BRANDT.
